UNITED STATES PATENT OFFICE

BRITTON E. BYRD, OF GASTONIA, NORTH CAROLINA, ASSIGNOR TO MILL DEVICES COMPANY, INC., OF GASTONIA, NORTH CAROLINA, A CORPORATION OF NORTH CAROLINA

KNOTTER

Application filed February 11, 1928. Serial No. 253,595.

This invention is an improvement in knotters, and more particularly in a knotter for threads of rayon, and the like.

The knotter forming the subject matter of Patent No. 1,572,181, granted on February 9, 1926, to Britton E. Byrd, provides a device for tying a weaver's knot, the form of knot being desirable because of its relatively small flat conformation.

In the said patent the knot is tied by means of a tying bill, and the threads are mechanically crossed on each side of the bill prior to the operation thereof, so that the bill in the first half of its revolution forms a loop 15 in one strand through which the other passes, and in the last half of its revolution cuts off and clamps one strand, and draws the cut end through the loop so formed, thereby completing the weaver's knot, which is strained and tightened as it is stripped from the bill.

While the said form of knot is entirely satisfactory for linen, cotton, and woolen threads of the usual twist, it has been discovered that in threads wherein the surface coefficient of friction is relatively small, and the fibers are relatively stiff, as for instance, in rayon or artificial silks of every character, the ends of the threads at the knot tend to back out, thus to loosen the knot.

A primary object of the present invention is the provision of a knotter, constructed and arranged to tie a weaver's knot like that of the patent previously mentioned, but having in addition mechanism for imparting an additional loop at the cut ends of the threads of one thread about the other, the additional loop serving as a stay or "scotch" for the said ends, to prevent "backing out" of said end.

With these and other objects in view the invention consists in the construction and novel combinations of parts fully described hereinafter, illustrated in the accompanying drawings, and pointed out in the claims appended hereto, it being understood that various changes in the form, proportion, size and minor details of construction within the scope of the claims, may be resorted to without departing from the spirit of the invention.

In the drawings forming a part hereof:—

Fig. 1 is a side view of the improved knotter.

Fig. 2 is an end view looking toward the point of the bill.

Fig. 3 is a section on the line 3—3 of Fig. 1. 55

Fig. 4 is a side view of the casing of the knotter with the handle removed, and with the sector guard broken away, showing the sector in one position.

Fig. 5 is a longitudinal section of Fig. 4. 60

Fig. 6 is a plan view of Fig. 4.

Fig. 7 is a view of the sector and the pinion operated thereby, with the casing indicated in dotted lines.

Fig. 8 is a similar view of the rocker. 65

Fig. 9 is a plan view of the casing with the cover removed and with parts broken away to show the completed operation of crossing, and the initial movement of the bill.

Fig. 10 is a longitudinal section of the casing looking at the opposite side from Fig. 5. 70

Fig. 11 is a perspective view of one end of the casing, showing the crossing mechanism, and with the crossing operation completed and the bill in its initial movement. 75

Fig. 12 is a plan view of the strands or threads in the position of Fig. 11.

Figs. 13 and 14 are views similar to Fig. 11, showing later positions of the tying bill, Fig. 13, showing the position at the beginning of the second half of the rotation, and Fig. 14, the position at the end of the complete rotation.

Fig. 15 is a plan view of the strands at the end of the operation shown in Fig. 13. 85

Fig. 16 is a view similar to Figs. 11, 13 and 14, showing the position of the parts during the stripping and straining of the knot.

Fig. 17 is a plan view of the strands prior to the stripping and straining of the knot. 90

In the present embodiment of the invention, the improved knotter includes a casing composed of side plates 1 and 2, connected by screw bolts 3, 4, 5 and 6, and held in spaced relation by a U-shaped member 7 and a cross plate 9, the member 7 and the plate 9 being arranged between the side plates, and clamped by the plates. The casing is completed by an arched cover 10, 95

which is secured to the plate 9 by a screw 11, being thus held in place on the casing.

A handle member 12 is secured to the side plate 1 by the screw bolt 3, and an adjustable hand loop 13 of leather or the like, is supported by the handle member. Beyond the U-shaped member 7, the side plates are outwardly offset, as clearly shown in Figs. 6 and 9, and the crossing mechanism to be described is mounted on these outwardly offset portions. The tying bill is arranged between the side plates, the bill including a spirally twisted shank 14, journaled at its rear end in the plate 9, as indicated at 15, and passing through alined openings in the sides of the U-shaped member 7. The bill which is of usual construction includes the fixed jaws 15 and 16, and the movable jaw 17, which is pivoted between the fixed jaws, and has a cam portion 18 cooperating with an eccentric opening 18a in the forward side of the U-shaped member, to move the movable jaw with respect to the fixed jaws when the bill is rotated by mechanism to be described. This is substantially the construction shown in the Byrd patent above referred to.

The bill is rotated by means of an elbow lever pivoted on the screw bolt 3, and including a thumb piece 19 for operating the same. The lever also includes a cam 20 and a fork composed of arms 21 and 22, between which the spirally twisted portion of the bill shank extends. The arms 21 and 22 are integral, and it will be obvious that when the lever is rocked by means of the thumb piece to cause the arms to move toward the point of the bill, the bill will be rotated. A spring 23 is provided for normally holding the lever in the position of Fig. 6, that is with the arms adjacent the bolt 5.

The mechanism for mechanically crossing the threads prior to the operation of the tying bill includes a pair of rockers 24 and 25, the former being pivoted at 26 to the plate 2, while the latter is pivoted at 27 to the plate 1. The plate 2 is cut away on the upper edge of the outwardly offset portion to form two notches or recesses 28 and 29, for receiving the two threads A and B, and the rocker is notched as indicated at 30, for receiving one of the threads, the white thread B in the present instance. In the normal position of the parts, the notch 30 is in register with the thread receiving notch 29, as indicated in Fig. 5, and the rear wall of the notch indicated at 24a extends upwardly between the notches 28 and 29, as clearly shown in this figure.

The pivotal connection 26 of the rocker is in vertical register with this wall 24a, and is between the guide notches 28 and 29. The arrangement is such that when the rocker is swung in a manner to be presently described, the outer thread B, that is the white thread in the drawing, is moved above

and to the rear of the inner thread A, that is, the black thread of the drawing.

The rocker 25 has two thread receiving notches 31 and 32, separated by an upright tongue or wall 33, and the outwardly offset portion of the plate 1 has thread receiving notches or recesses 34 and 35, registering with the notches 31 and 32 respectively when the parts are in normal position, and with an upstanding tongue 36 between the notches, registering with the tongue 33 when the parts are in normal position. This tongue 36 is curved inwardly at its top, as shown, for a purpose to be presently described.

In order to insure that the threads will be properly laid in the receiving notches or guides 28-29, and 34-35, a separating arm 37 is provided, this arm extending from one of the arms of a stirrup 38, pivoted to an upwardly extending extension 39 on the side plate 1. The side plate 2 has a similar extension 40, and a screw bolt 40a connects the extensions near their tops. The arms of the stirrup 38 are journaled on this bolt, one on each side of the extension 39, and a spring 38a is arranged between one arm and the extension, the spring acting normally to hold the stirrup and the separating arm in the position of Fig. 10.

The free end of the arm 37, when the parts are in normal position, is just above the wall 24a, before mentioned, and spaced apart a slight distance therefrom. The tongue 36 acts as a stop for limiting the downward movement of the arm 37, to the position shown in Fig. 10. It will be apparent from the description that it will be exceedingly difficult, and practically impossible without intention, to place the two threads in one thread receiving notch at either side of the casing. This can only be done by passing one of the threads between the free ends of the arm 37 and the wall 24a.

The rocker 24 is moved by means of a slide plate 41, having guided movement on the outer face of the side plate 2, and connected to one end of a cross bolt 43, which is movable longitudinally of the casing in slots 44 in the side plates. The bolt or shaft 43 normally rests in a notch or recess 45 in the cam 20 before mentioned, and the forward wall of the notch is extended above the curved upper edge of the cam as shown at 46. When downward pressure is made upon the thumb piece of the lever, the shaft or the bolt 43 is constrained to move forwardly by its engagement with the rear wall of the notch 45. Upward movement of the shaft is prevented by the walls of the slots 44, and this forward movement of the shaft is continued until in its travel in the slots it passes above the level of the rear wall of the notch 45. The upper edge of the cam behind the notch 45 is concentric with the shaft 3, so that no further movement is imparted to the shaft, until the thumb piece 19

is released. As the lever moves to its normal position, the shaft rides on the curved upper edge of the cam until it registers with the notch 45. At this moment the extension 46 of the front wall of the notch engages the shaft, moving it rearwardly, and again into the notch.

The mechanism for swinging the rocker 25 includes a sector 47, which engages a pinion 48 rigid with the pivot pin or shaft 27 of the rocker. The sector has a radial arm 49 which is pivoted to the side plate 1 as indicated at 50. The arm has a slotted extension 51 which is engaged by the end of the shaft 43. When the shaft moves forwardly under the impulsion of the lever 19, as previously described, the arm and the sector are swung sharply downward, and the shaft 27 is rotated. The extent of movement, and the toothed connection are such that substantially two complete rotations are imparted to the rocker. Normally the rocker stands in the position of Fig. 11, and at the end of the movement of the sector it is in the position of Fig. 14. Thus two complete turns as shown in Fig. 12, are imparted to the strands A and B. That is, the strand B may be considered as being wrapped twice about the strand A.

In order to cover the slot 44 in the plate 1, a plate 52 is secured to the shaft 43, on the outer face of the plate 1, and moves with the shaft. A guard 53 for the sector is secured to the body of the plate 1, and to the outward offset portion thereof. One strand A is cut by the tying bill, and clamped between the cutting blade and one of the fixed jaws. The other strand is cut by mechanism shown more particularly in Figs. 14 and 16.

The said mechanism includes a fixed blade 54, which is one of the arms of a stirrup, extending on the inner face of the outwardly offset portion of the plate 1, the other arm being on the outer face thereof, and being secured to the plate by a screw bolt 55. A movable blade 56 is pivoted on the bolt 55, and the blade has a laterally extending hollow pin 57, which engages a slot 58 in a lever 59. The lever is pivoted on the bolt 6 before mentioned, as shown in Fig. 10, and the rear end thereof is forked, the fork consisting of a long arm 60, and a short arm 61. The long arm rests upon a pin 62 in the face of the cam 20 before mentioned. When the lever 19 is swung downwardly the pin moves along the underface of the long arm until it strikes the short arm, at which time the movable blade is swung into cutting position, and the thread or strand A is cut. When the cam moves rearwardly to normal position, the pin engages the long arm, and swings the lever to open the blades. In order to prevent disengagement of the hollow pin 57 from the slot 58, a guard 63 is provided. The guard is held in place by the screw 55, and the free end

thereof engages within the hollow of the pin as shown in Figs. 14 and 16.

The straining and stripping device is constituted by a lever 65 pivoted to the plate 1 at 66. This lever at its inner end has a fork including a long arm 67, and a short arm 68. The arm 21 of the fork on the cam 20 bears against the underside of the long arm. When the lever 19 is swung to rotate the bill, the free end of the fork arm moves against the curved under edge of the long arm of the lever without moving the lever. When, however, the fork arm 21 engages the short arm 68, the lever is swung, and the return of the lever 19 to normal position returns the lever 65 also to normal position. The forward end of the lever has a depending arm 69 provided at its lower end with a laterally extending hook 70. The hook extends beneath the tying bill, and to a position between the same and the plate 2.

When the lever is swung as above described, the stripper engages the strands between the bill and the rocker 24, and strips them from the bill, at the same time straining the knot. The thread separating arm 37 is normally positioned in the path of movement of the stripper, and for this reason the said arm is pivoted and spring pressed into normal position, but is capable of yielding as the stripper swings upward to offer no impediment to the movement of the stripper. The stripper does not move high enough to entirely disengage the separator arm, which for this reason is not moved by the spring until the stripper returns to normal position.

The operation is as follows: The threads are laid in the guide notches of the plates 1 and 2, the correct position being insured by the separator arm. The lever 19 is now swung by means of the thumb piece. The first operation is the crossing of the threads adjacent the plate 2. The rocker 22 moves the outer or white thread inwardly above the inner or black thread, and to the inner side thereof, thus crossing the threads between the bill and the plate 2, it being understood that the threads are on opposite sides of the bill. The same movement rotates the rocker 25 through two complete revolutions, and the strands between the bill and the plate 1 are wrapped about each other in the manner shown in Fig. 12. Near the completion of these movements, the bill has commenced to rotate, and the point thereof moves down between the crossed threads between the bill and the plate 2, that is to the space indicated at C in Fig. 12. Further movement of the bill swings it to the position of Fig. 13, and the movable jaw is opened. By the movement of the rocker 25, the inner or black thread is in register with the space between the open jaws of the bill, and moves into such space as the bill completes the first half

of its rotation. Meanwhile the inner or black thread has been looped about the bill and over the white thread, as clearly shown in Fig. 15. When now the black thread is cut and grasped by the bill, the cutting mechanism for the white thread comes into operation, this thread being clipped by the movable and the fixed blade. Immediately afterwards the stripper begins its upward movement. It engages between the black and the white threads at the left of the bill in Fig. 14, and draws the form off the bill, the clamped end of the black thread B being thus drawn through the space D in Fig. 15 from above downward. This results in the formation of the knot shown in Fig. 17, which is a weaver's knot, with a "scotch" or stay at the outer side thereof. The extra loop providing the stay is caused by the extra 20 twist imparted to the strands by the pivoted rocker 25.

What is claimed as new is:—

1. Mechanism for tying a weaver's knot, including a rotary tying bill, means to cross the threads on one side of the bill, and means on the other side to wind the threads about each other through a double turn for the purpose specified.

2. In a knotter including a rotary tying bill, means to rotate the threads one about the other, thereby to move them into crossed relation on opposite sides of the bill, means to operate the thread moving means and the bill in sequence, and mechanism to impart a greater movement to one of the thread moving means than the other for the purpose specified.

3. In a knotter including a rotary tying bill, means to rotate the threads one about the other, thereby to move them into crossed relation on opposite sides of the bill, means to operate the thread moving means and the bill in sequence, and mechanism to impart a greater movement to one of the thread moving means for the purpose specified, the thread moving means including rockers, each having seats for receiving the threads in spaced relation, and connections between the operating means and the rockers for moving the same.

4. In a knotter including a rotary tying bill, means to rotate the threads one about the other, thereby to move them into crossed relation on opposite sides of the bill, means to operate the thread moving means and the bill in sequence, mechanism to impart a greater movement to one of the thread moving means than the other for the purpose specified, the connection for the last named 60 rocker including a pinion thereon, and a sector cooperating therewith and operated by the operating means for imparting the amplified movement.

5. In a device of the class described, a tying bill, means to position a pair of threads for

knotting by the bill, including means to move the threads at one side of the bill in opposite directions to cross said threads, and means at the other side to rotate the threads about each other through a double turn for the purpose specified.

6. A knotter including a tying bill, means for supporting a pair of threads in substantially parallel relation on opposite sides of the bill, means to rotate the bill, means to cross the threads on opposite sides of the bill prior to the rotation of the bill, said means including rockers operated by the bill rotating means, and means to impart a greater movement to one of the rockers than the other.

7. In a knotter, a tying bill, means to support a pair of threads in spaced relation on opposite sides of the bill, means to rotate the bill, means on opposite sides of the bill to cross the threads, said means operated by the bill rotating means, and means in connection with one of said means for imparting a greater movement thereto than to the other for the purpose specified.

8. In a knot tying device, in combination, a tying bill mechanism having cutting and clamping means, and means for positioning a plurality of threads to be acted upon by the tying bill mechanism to produce a knot, said means including mechanism for moving the threads into crossed relation at one side of the bill, and means at the other side for moving the threads into double crossed relation.

9. In a knotter, including a frame, and a tying bill rotatable therein, means to rotate the bill, said frame having thread holding means at opposite sides of the bill, an auxiliary thread cutting means supported by one of the holders, said means including a blade fixed to the holder, and a movable blade pivotally and detachably connected with the fixed blade, and means operated by the bill rotating means for moving the movable blade.

10. In a knotter, including a frame, and a tying bill rotatable therein, said frame having thread holding means at opposite sides of the bill, an auxiliary thread cutting means supported by one of the holders, said means including a blade fixed to the holder, and a movable blade pivotally and detachably connected with the fixed blade, the detachable connection including a screw engaging the fixed blade and on which the movable blade is rotatable, and a post on the movable blade for engagement by the operating mechanism.

11. In a knotter, including a frame, and a tying bill rotatable therein, said frame having thread holding means at opposite sides of the bill, an auxiliary thread cutting means supported by one of the holders, said means including a blade fixed to the holder, and a movable blade pivotally and detachably connected with the fixed blade, the detachable connection including a screw engaging the fixed blade and on which the movable blade

is rotatable, a post on the movable blade for engagement by the operating mechanism, and a spring plate held by the screw and engaging the post.

5 12. In a knotter, including a frame, and a tying bill rotatable therein, said frame having thread holding means at opposite sides of the bill, an auxiliary thread cutting means supported by one of the holders, said means 10 including a blade fixed to the holder, and a movable blade pivotally and detachably connected with the fixed blade, and means operated by the rotation of the bill for moving the movable blade, the fixed blade being a 15 part of a stirrup including a body and arms arranged on opposite sides of the holder, one of the arms being the fixed blade, and the other being connected to the holder.

13. In a knotter, including a rotary tying bill, holders at opposite sides of the bill to support a plurality of threads lying alongside each other, means to rotate the bill, means operated by the bill rotating means to impart rotary movement to the holders in 25 planes transverse to the length of the threads, whereby to move the threads to crossed relation, and means between the operating means and one of the holders to move the same through a greater arc than the other.

30 Signed at Gastonia, in the county of Gaston and State of N. Carolina, this 9th day of February, A. D. 1928.
